UNITED STATES PATENT OFFICE.

EPHRAIM GOLDFAIN AND SAMUEL FOWLER, OF OKLAHOMA CITY, OKLAHOMA.

ELECTRIC FAN.

Application filed October 25, 1926. Serial No. 144,053.

This invention relates to an improved electric fan of the portable type.

The invention has more specific reference to a structure of this kind wherein the fan 5 proper is mounted for rotation about a true horizontal axis and the motor and housing is mounted upon the standard to move about a true vertical axis, means being provided for actuating said parts, whereby to produce a straight forward current of air from 10 the fan, and to cause this current to sweep in a step by step manner throughout a complete circle.

The details for accomplishing this improved result will become more readily apparent from the following description and 15 drawings.

In the drawings:—

Figure 1 is a side view of the improved 20 structure.

Fig. 2 is a section taken on the line 2—2 of Fig. 1.

Fig. 3 is an enlarged detail sectional view 25 showing certain of the parts more in particular.

Referring to the drawings, it will be seen that the reference character 1 designates the upright of a stationary supporting base, the same having a somewhat spherical enlargement or head 2 at its top. Then, as shown 30 in Fig. 3, a socket 3 is formed in said top. Resting on the top of the upright is a ring 4 carrying a central depending sleeve 5 fitted into and terminating in spaced relation with 35 the bottom of said socket. Retaining screws 6 serve to secure the sleeve to the upright.

Pinned or otherwise rigidly secured to the ring 4, inward of the marginal portion is a ratchet annulus 7. Surrounding this, 40 is a relatively movable collar 8 carrying a set screw 9 on one side, and carrying a spring pressed ratchet pin 10 on its opposite side. The small housing 11 is made to accommodate and receive this pin 10.

Obviously, the pin extends into the space 45 shown in Fig. 2 and engages the ratchet teeth. The fan is represented by the reference character 12, and as before stated, this is secured upon a shaft 13 rotatable on 50 a horizontal axis. The shaft is driven by a conventional motor (not shown), in the housing or casing 14. This casing as is better shown in Fig. 3 has a neck 15 at its bottom which rests upon a circular bearing 55 plate 16 which in turn bears upon a washer 17 resting on the aforesaid ratchet 7.

Connected to the collar 8 is an operating link 18 which has pivotal connection as at 19 to the ratchet pin housing 11. The opposite end of this link is connected to an eccentric operating device generally represented by the reference character 20. The same is of well known construction.

With the arrangement described, it is obvious that when the set screw 9 is locked 65 against the ratchet 7, the casing and fan structure will simply be oscillated in a well known manner. By loosening the set screw however, a pawl and ratchet mechanism is permitted to come into play in order to move 70 the entire casing and fan, as a unit, in a step by step manner throughout a complete circle. Thus, we have a fan which projects 75 a straight-forward current of air which can be caused to sweep throughout a complete circle.

Carried by and depending from the center of the motor casing 14 is a hollow spindle 21 which extends down into the aforesaid sleeve 5 and is rotatable therein on a vertical 80 axis. At its bottom this spindle is provided with an annular groove into which the inner end portion of the aforesaid bolts 6 extend as shown plainly in Fig. 3. Arrangement 85 within the spindle of the electricity conductors, 22, and 23 are connected together by a ball and socket joint as at 24. These conductors are enclosed in an insulation casing 25 fitted snugly into the bore of the hollow 90 spindle.

It is thought that by considering the detailed description in connection with the operation, and construction shown in the drawings, a clear understanding of the invention will be obtained. In view of this, 95 a more lengthy description is thought unnecessary.

While the preferred embodiment of the invention has been shown and described, it is to be understood that minor changes coming within the field of invention claimed may be resorted to if desired.

Having thus described our invention, what we claim as new is:—

In an electric fan, an upright support, a head rotatable on the support and including a fan rotatable about an axis at a right angle to the axis of rotation of the head, an eccentric operatively connected with the fan, an annular ratchet on the support, an annulus circumjacent the ratchet, a set screw in the annulus and engageable with the 105 110 115

ratchet to lock the ratchet and annulus together, a spring pressed pawl mounted in the annulus to engage the ratchet, and a link engaged with the eccentric and the annulus so that with one operation of the fan oscillatory movement is imparted to the head when the set screw is engaged with

the ratchet or rotary intermittent motion is imparted to the head when the set screw is disengaged from the ratchet.

In testimony whereof we affix our signatures.

EPHRAIM GOLDFAIN.
SAMUEL FOWLER.
